UNITED STATES PATENT OFFICE.

EVELYN ASHTON FLETCHER, OF TORONTO, CANADA.

DESIGN FOR A KEYBOARD.

SPECIFICATION forming part of Design No. 29,497, dated October 18, 1898.

Application filed October 26, 1897. Serial No. 656,472. Term of patent 7 years.

To all whom it may concern:

Be it known that I, EVELYN ASHTON FLETCHER, a subject of the Queen of Great Britain, residing at the city of Toronto, in the county of York, in the Province of Ontario, Canada, have invented and produced a new and original Design for Keyboards, of which the following is a specification, reference being had to the accompanying drawings, forming part thereof.

The drawings represent a plan view of the keyboard in Figure 1, and in Fig. 2 a longitudinal section.

The leading feature of my design consists in the representation of a single staff interrupted near the center, where a double staff is represented, the lines of the portions of the single staff being arranged intermediate of the double staff.

The representation of a single staff and its

accessories is imprinted on the white keys, this being interrupted near the center of the keyboard, and from this point between the interrupted staff a double staff is imprinted, extending in parallel lines. The lines of the single staff are shown at A B and the double staff intermediate of the lines of the single staff at D. The black keys E have imprinted a double set of staves and accessories arranged in parallel, as at F and G, and portions of the white keys are provided with a single staff H and accessories, forming a continuation of the staff G of the black keys.

I claim—

The design for a keyboard herein shown and described.

EVELYN ASHTON FLETCHER.
